FINDING FOR CLASPS

George W. Jenckes, Cranston, R. I., assignor to
 D. M. Watkins Company, a corporation of
 Rhode Island

Application June 22, 1935, Serial No. 27,920

4 Claims. (Cl. 24—251)

My invention relates to a clasp finding of the type which requires merely the mounting of an ornamental member thereon to complete the entire clasp.

5 The essential objects of my invention are security against accidental disengagement of the clasp from the garment; compactness; inexpensiveness of construction; and a minimum number of parts.

10 With the above and other objects and advantageous features in view, the invention consists in the arrangement of parts more fully disclosed in the detailed description following, in conjunction with the accompanying drawing, and 15 more specifically defined in the claims appended thereto.

In the accompanying drawing forming a part of this specification,

20 Figure 1 is a rear elevation of my finding or component ready for the reception of the ornamental member,

Figure 2, a section, partially in side elevation, of the same with the parts in locked position taken on line 2—2 of Figure 1,

25 Figure 3, a like section of the same, with the parts shown in an unlocked position,

Figure 4, a transverse section taken on line 4—4 of Figure 1,

Figure 5, a detail perspective view of the mounting member,

Figure 6, a side elevation of the bolt, and

Figure 7, a like elevation of the finding carrying the ornamental member.

Similar reference characters indicate similar 35 parts throughout the views.

In its present and preferred embodiment my clasp or clip finding comprises a jaw member 9 destined to constitute the rear jaw of the completed clasp. The forward pointed portion of the 40 jaw has integral angularly directed spurs or prongs 10; and lateral rectangular notches 11 near the rear end of the jaw form pivotal lugs or projections 12.

The rear face of the jaw is provided with a 45 longitudinal forwardly directed depression 14, midway its width, extending from a medial portion to its rear end, and bridged intermediate its length by an integral strap 15 cut and rearwardly bent from the material of the jaw. The forward 50 portion of the depression is provided with a longitudinal slot 17, and the jaw is provided with an opening 18, bisecting the depression near its rear end, thus dividing the depression 14 into a guideway portion 19 and a socket portion 20.

55 A bolt 21 of thin resilient material is provided

comprising, as shown in Figure 6, a flat shank portion 22 and an end portion 23 of reduced width. Intermediate its length the material of the shank portion is arcuately bent to form a slight swell or shoulder 24, and a knob or thumb piece 25 is fixed 5 to or integral with the end portion of the shank 22. In this instance the operating projection 25 comprises a head 26, a shank portion 27 extending through a perforation 28, and a riveted over end portion 29. The bolt is retained in the guideway portion 19 of the depression by the strap 15 and, when in locked position, registers with the socket portion 20 of the depression. The slot 17 accommodates the projecting end 29 of the bolt member 25 when the latter is moved. The 10 resilient friction shoulder 24 cooperates with the strap 15 to assist in preventing the accidental disengagement of the bolt from the socket portion 20 when they are interengaged as shown in Figure 2.

20 A mounting member 31 includes an oblong body 32 and downwardly directed ears 33 upon its ends provided with perforations 34 through which the pivotal lugs 12 of the jaw pass. A rectangular depending locking loop 36 integral with the forward edge of the body 32 is movable through the opening 18 of the jaw, in which position the eye or open portion 38 of the loop is in alignment with the depression 14 of the jaw and in the path of the bolt 21, permitting the portion 23 of the 30 latter to pass freely therethrough into frictional engagement with the socket portion 20 when the bolt is advanced in its guideway. In Figure 2 the bolt is shown so advanced. In Figure 3 the bolt is shown withdrawn and the body of the member 31 shown free to assume any desired angular position 35 relatively to the jaw 9.

My above described component or finding may now be transformed by the purchaser into a complete clasp by the addition of a complementary 40 jaw or face plate of any preferred shape or design.

When, as shown in Figure 7, the ornamental face plate or jaw 40 has been by solder or other means fixed to the body portion 32 of the mounting member 31 the forward or work engaging portion of said jaw rests upon the clothing engaging prongs 10 of the corresponding portion of the cooperating jaw 9 with the jaws in substantial parallelism with each other. In this figure 50 the complete clasp is shown with the jaws closed, and locked together in closed position.

To apply the clasp the bolt is withdrawn and the jaws distended to receive the article to be 55 engaged therebetween, and then compressed

thereupon, during which compression the bolt is advanced to locked position.

5 The laterally projecting pivot members 12 dispense with the necessity of vertical bearing lugs upon the jaw 9, thus enabling the jaws 9 and 40 to be in parallelism and adjacent each other, thus imparting compactness to the clasp.

10 The presence of a positive lock makes it possible to dispense with the use of fallible and weak spring devices for forcing the jaws towards each other, and to dispense with stop lugs of any kind on the mounting member.

I claim:—

15 1. A finding for a clasp comprising a jaw member provided with a longitudinal depression and with an opening in the depression, a mounting member for receiving another jaw member of the clasp pivotally mounted upon the first jaw member including a locking loop adapted to extend into said opening, and a bolt slidably mounted in the depression movable through the loop.

20 2. A finding for a clasp comprising a jaw member provided with a longitudinal depression and with an opening in the depression, a mounting member for receiving another jaw member of the clasp pivotally mounted upon the first jaw member including a locking loop adapted to ex-

tend into said opening, a strap integral with the first jaw member bridging the depression, and a bolt slidably mounted in the depression movable through the loop in contact with the strap.

3. A finding for a clasp comprising a jaw member provided with a longitudinal depression and with an opening in the depression, a mounting member for receiving another jaw member of the clasp pivotally mounted upon the first jaw member including a locking loop adapted to extend 10 into said opening, a strap integral with the first jaw member bridging the depression, and a bolt slidably mounted in the depression movable through the loop, and a friction shoulder upon an intermediate portion of the bolt engageable with 15 the strap.

4. A finding for a clasp comprising a jaw member provided with a longitudinal depression, a longitudinal slot in the depression and an opening in the depression, a mounting member for 20 receiving another jaw member of the clasp pivotally upon the first jaw member including a loop adapted to traverse the opening, a bolt slidably mounted in the depression and movable through the loop, and a knob upon the bolt including a 25 portion registering in the slot.

GEORGE W. JENCKES.
